SEYMOUR M. NILES, OF SAUGUS, MASSACHUSETTS.

HOLLOW SHOE-FORM.

1,156,429.

Patented Oct. 12, 1915.

Application filed January 2, 1913. Serial No. 739,689.

To all whom it may concern:

Be it known that I, SEYMOUR M. NILES, a citizen of the United States, residing at Saugus, county of Essex, State of Massachusetts, have invented a certain new and useful Improvement in Hollow Shoe-Forms, of which the following is a specification, reference being had therein to the accompanying drawings.

10 The invention relates to a hollow metallic last.

The last or form consists essentially of a closed and seamless hollow metallic form, preferably having a transverse brace and a 15 vertical brace entirely inclosed within the form and secured in position by projections from the inner face of the form integral therewith and engaging with said braces.

20 The process of making the said form comprises essentially the forming of a solid duplicate or mold of a last of some substance which is cohesive but which fuses at a lower temperature than the hollow metallic last which is to be produced, inserting into this 25 mold the rods which are to form the braces of the last, coating the entire surface of the said mold and the ends of said rods with a coating of electric conducting material, such for instance as graphite, making an electrolytic deposit of metal on the entire surface of the mold except for a small outlet hole through the shell formed by the metal deposit, then heating the metal shell and inclosed mold thus formed sufficiently to fuse 30 the mold so that it will flow out of the hole in the metallic shell.

35 The invention will be fully understood from the following description taken in connection with the accompanying drawings, 40 and the novel features thereof will be pointed out and clearly defined in the claims at the close of this specification.

In the drawings: Figure 1 is an elevation showing the fusible mold which is a duplicate 45 of the model, with the rods for the braces inserted therein and a suspension hook inserted in the heel so that it may be hung toe downward. Fig. 2 is a view similar to that shown in Fig. 1 after the mold has 50 been coated with the electric conducting material. Fig. 3 is a view showing the coated mold suspended in an electrolytic solution and mechanism for rotating the pattern while securing the deposit. Fig. 4 is a vertical longitudinal section showing the mold 55 and metallic coating after it is removed

from the electrolytic bath, and before the suspension hook has been withdrawn. Fig. 5 is a longitudinal section of the completed last after the hook and the fusible mold 60 have been removed. Fig. 6 is a vertical cross section of the finished last on line 6—6 of Fig. 5.

Referring now to the drawings,—1 represents a fusible mold or duplicate of the 65 original model and is made of a cohesive material which is fusible at a relatively low temperature. One way of making this fusible mold is to make a plaster of Paris mold of the model.

70 Then the inside of each half of the plaster of Paris mold is coated with graphite or some other suitable substance to prevent the fusible substance from adhering to the plaster of Paris. Then melted wax or some other suitable fused substance is run into the plaster of Paris mold and allowed to solidify, forming a duplicate of the model.

75 The rods for the braces are then inserted into the body of the fusible mold 1, preferably two rods, one of these being for a transverse brace 3 above the arch portion and about half way to the top, and the other brace 4 being a vertical brace in the fore part, extending from the top to the bottom. 80 Each of these rods 3, 4, is preferably formed with a recess or depression 6 in each end. The hook portion 7 of a wire hanger 8 is then inserted into the heel end of the fusible mold so that the said fusible mold may be 85 suspended in the electrolytic bath. After the rods, 3, 4 are inserted, the entire surface of the fusible mold and the exposed ends of the rods 3, 4 are coated with a suitable electric conducting material 2, preferably 90 graphite, taking care that the depressions 6 in the ends of the rods 3, 4 are merely coated, but not filled up, it being important that there shall still be a surface depression after the coating is applied. The fusible 95 mold 1 is then suspended in an electrolytic bath 9 by means of the hanger 8 which is connected with mechanism whereby the mold 1 is given a slow rotation on its axis while the metallic deposit is taking place so 100 that there will be an even coating of the metal.

105 Any suitable means may be employed for rotating the mold, the means shown consisting of a bevel gear 10 through the hub of which the wire hanger extends and which is clamped therein, said bevel gear 10 mesh-

ing with a gear 11 on a driving shaft 12. The wire hanger 8 is connected by a wire 13 with one pole of a battery 14 which is diagrammatically represented, the other 5 pole of the battery being electrically connected by a wire 15 with the metallic anode 16 which is preferably copper but may be of any other suitable metal. When the electric connections are made and the current 10 turned on, the rotating mechanism for the fusible mold being in operation, the metal from the copper anode will be deposited on the entire surface of the mold, entering the depressions in the ends of the rods 3, 4 15 and forming protuberances 18. When a deposit of the desired thickness has been made, the current is shut off and the rotation of the mold is stopped and the mold with its metallic coating or shell 17 is withdrawn from 20 the bath. Any extra deposit of metal around the wire hanger where the wire passes through the shell into the mold should be scraped away, and then by tipping the wire and pulling it at the same 25 time the wire can be drawn out without leaving any hole except the size of the wire, where the wire passes through.

The metallic shell 17 with its inclosed fusible mold is then heated sufficiently to reduce the fusible mold to a fluid. If wax or 30 some other readily fusible material is used for the mold, the fusion may conveniently be accomplished by immersing the shell with inclosed mold in hot water.

When reduced to a fluid, the fluid substance will flow out of the small hole left by the withdrawal of the wire, leaving the shell entirely closed except for the small hole left by the wire, and the brace rods 3, 4 40 will be securely held in position by the protuberances 18 engaging with the depressions 6. The device can be used either as a last or as a shoe form and will be very light and strong.

What I claim is:

1. A hollow metallic shoe form or last having a brace rod extending from the interior surface of one wall to the interior surface of another wall, said brace being formed with a recess in each end, and the 50 inner surfaces of the said walls having integral therewith protuberances which engage the recesses in said braces.

2. An integral, hollow, seamless metallic shoe form or last closed on all sides and having a brace rod extending from the interior surface of one wall to the interior surface of another wall, said brace being formed with a recess in each end and the inner surfaces of the said walls having integral therewith protuberances which engage the said braces in said recesses.

In testimony whereof I affix my signature, in presence of two witnesses.

SEYMOUR M. NILES.
